J. O'BRIEN.

Grate Damper.

No. 18,885.

Patented Dec. 15, 1857.

UNITED STATES PATENT OFFICE.

JOHN O'BRIEN, OF NEW YORK, N. Y., ASSIGNOR TO OWEN COLLINS AND JOHN DUNLEY, OF SAME PLACE.

GRATE-DAMPER.

Specification of Letters Patent No. 18,885, dated December 15, 1857.

To all whom it may concern:

Be it known that I, JOHN O'BRIEN, of the city, county, and State of New York, have invented a new and useful Improvement in 5 Dampers for Open Grates; and I do hereby declare that the following is a full, clear, and exact description of the same, reference being had to the accompanying drawings, making a part of this specification, in 10 which—

Figure 1 is a transverse vertical section of a grate, with my improvement applied to it, which improvement is also bisected, (x) (x) in Fig. 2 showing the plane of section. Fig. 15 2 is a front view of the same.

Similar letters of reference indicate corresponding parts in each of the several figures.

The invention is designed to obviate the 20 objection to open grates, viz., the great consumption of fuel occasioned by the large amount of heat which passes up the chimney or flue.

To enable those skilled in the art to fully 25 understand and construct my invention, I will proceed to describe it.

A, represents an open grate of the usual construction, and B is my improved damper placed some distance above the grate. This 30 damper is formed of a rectangular cast iron frame (a) which is fitted between jaws (b) one at each end of the flue. The frame (a) is cast with horizontal bars (c) across it. These bars are of V-form, transversely, as 35 shown clearly in Fig. 1, and any proper number may be used. Three, however, are shown in the drawings.

Within the frame (a) a frame (d) is fitted, the lower end of the frame (d) being 40 connected by joints (e) to the lower end of the frame, (a). The frame (d) is cast with horizontal bars (f), which, when the frame (d) is upon the frame (a), will fill the spaces between the bars (c). This is clearly 45 shown in Fig. 1. The bars (f) are each provided with a flanch (g) which flanches project out at right angles from the bars (f).

The frame (a) is placed in an inclined position, as shown clearly in Fig. 1, and when 50 a full or strong draft is desired the frame (d) is thrown back, as shown in red in Fig. 1, the passage of the full or strong draft being indicated by the red arrows in Fig. 1.

A medium draft is obtained by having the 55 frame (d) secured a short distance back

from the frame (a). When a small or weak draft is only desired, the frame (d) is allowed to rest upon the frame (a). By this means the damper will be nearly but not entirely closed, for the bars (f) do not come 60 in contact with the bars (c), and the openings or spaces between the edges of the bars (f) and the back edges of the bars (c) are sufficiently wide to allow the gas to escape up the chimney or flue, but not the heat, the 65 draft being merely sufficient to keep up the necessary combustion and carry off the gas. The black arrows show the direction of the gases.

The V-form of the bars (c) and the 70 flanches (g) on the bars (f) are for the purpose of deflecting the heat, and causing it to be thrown out into the room, as indicated by the arrows 1.

I am aware that dampers for open grates 75 have been previously devised for the same purpose. A perforated damper was recently patented; but it does not fully answer the intended purpose. The perforated openings cannot be enlarged nor contracted, and chimneys vary so very materially as regards their strength of draft that the perforated damper will suit in some cases and not in others. When fitted in some chimneys, the draft is not sufficiently strong to carry off the gas, 80 and when fitted in others the draft is strong enough to allow a vast amount of heat to pass through the perforated damper and up the chimney.

I do not claim, broadly, the employment 90 of dampers composed of two parts, one of which is provided with angular projections, for I am aware that an example of such a device is seen in the rejected application of J. H. Wilkinson, May 28, 1856. But in the 95 above device one portion of the damper slides over the other, rendering its application to fire-places or its use as a grate-damper, difficult if not impossible. But by hinging the frames (a) and (d) together, as 100 herein shown, the damper becomes perfectly adapted to the fire-place, and forms a new and highly useful improvement.

I would remark that the frame (d) may be retained at any point by a rod (h) having a projection (i) upon it, said rod passing through a slot (j) in one side of the frame.

It will be seen that my improved damper 110 may be adjusted to suit the draft, and there-

fore the invention may be advantageously applied in all cases.

Having thus described my invention, what I claim as new, and desire to secure by

5 Letters Patent, is:

The employment within a fire-place, of a damper B, composed of two frames (a) and

(d), when one of said frames (d) is hinged to the other frame (a), as and for the purposes herein specified.

JOHN O'BRIEN.

Witnesses:

OWEN COLLINS,
JOHN DUNLAY.
